(57) **CLAIM**

The ornamental design for footwear, as shown and described.

DESCRIPTION

FIG. 1 is a top plan view of footwear showing my new design.

FIG. 2 is a front elevation view thereof.

FIG. 3 is a rear elevational view thereof.

FIG. 4 is a right side elevational view thereof.

FIG. 5 is a left side elevational view thereof; and,

FIG. 6 is a top plan view thereof.

The broken lines in the photographs are for the purpose of illustrating environment and form no part of the claim.

1 Claim, 4 Drawing Sheets
